AIR FILTERING APPLIANCE

Wolodymyr Diachuk, 3000 S. Highway 100,
St. Louis Park, Minn. 55416

Filed Jan. 12, 1973, Ser. No. 322,955

Term of patent 14 years

Int. Cl. D23—99

U.S. Cl. D23—149

FIG. 1

FIG. 2

FIG. 3

FIG. 4

FIG. 5

FIG. 6

FIG. 7

FIG. 1 is a top plan view of an air filtering appliance showing my new design;

FIG. 2 is a bottom plan view of FIG. 1;

FIG. 3 is an end elevational view of the front end corresponding to the right end of FIG. 1;

FIG. 4 is an end elevational view of the rear end corresponding to the left end of FIG. 1;

FIG. 5 is a side elevational view of the right side of FIG. 4 with parts of the side wall broken away to show the structure of the ends and bottom;

FIG. 6 is a side elevational view of the left side of FIG. 4; and

FIG. 7 is a sectional view taken along the line 7—7 of FIG. 6.

I claim:

The ornamental design for an air filtering appliance, substantially as shown and described.
